JALOUSIE WINDOW LOUVER

John M. Sprow, North Miami, Fla.

Application August 18, 1950, Serial No. 180,260

3 Claims. (Cl. 20—62)

1

This invention relates to improvements in jalousie windows, and more particularly to means for removably mounting individual louvers of such windows in the frames thereof, the primary object of the invention being to provide such mounting means in the form of clips composed of two sections which are frictionally engaged in such a manner that the sections can be quickly and easily separated to enable removal of a damaged louver and can be quickly and easily re-engaged to install a replacement louver, all without removing or working upon the window frame or in any way damaging or defacing the frame or subjecting the louvers, which are usually of glass, to marring or breakage.

Other important objects and advantageous features of the invention will be apparent from the following description and the accompanying drawings, wherein merely for purposes of illustration herein, a specific embodiment is set forth in detail.

In the drawing, wherein like numerals designate like parts throughout the several views:

Figure 1 is a fragmentary transverse vertical section taken through a jalousie window frame showing louvers mounted therein in accordance with the present invention, only one of the side members being shown;

Figure 2 is an enlarged inside elevation of one of the mounting clips;

Figure 3 is an outside elevation thereof;

Figure 4 is a top plan view of Figure 2;

Figure 5 is an outer end elevation, looking from right to left in Figure 3;

Figure 6 is an inner end elevation, looking from left to right in Figure 3; and

Figure 7 is a transverse vertical section taken on the line 7—7 of Figure 2.

Referring in detail to the drawing, the numeral 9 generally designates a jalousie window frame having the vertical side members 10, only one of which is shown, between which the glass or other similar material louvers 11 are horizontally disposed in vertically spaced relation in declining planes. In accordance with the present invention the opposite ends of the louvers 11 are secured in clips, generally designated 12, which mount the louvers on the window frame side members 10.

The clips 12 are similar but are reversed in position on the opposite ends of the louvers 11. Each clip 12 comprises a bracket section A, adapted to be secured in place on the frame side member 10 by means of rivets 13 or other suitable means, and a holder section B, in which the

adjacent end of the louver is supportably inserted and confined.

The bracket section A comprises a plane vertical plate 14, adapted to engage the inner side of the frame member 10 flatwise, formed with vertically spaced holes 15 and 16 to pass the securing rivets 13. The plate 14 has a perpendicular rear edge 17 and a forwardly declining forward edge 18, and a forwardly declining and less angulated lower right angular edge on which is a laterally inwardly projecting plane flange 19 having a free edge 19' parallel to the plate 14. The flange 19 has the declination corresponding to the desired declination of the louver 11.

15 The holder section B comprises a channel form comprising upper and lower parallelly spaced sidewalls or flanges 20 and 21 respectively, spaced to snugly receive therebetween an end of the associated louver 11, and connected at their 20 outward longitudinal edges by a web 22. The lower flange 21 is plane and uninverted and its elevated end 23 terminates in downwardly or laterally inwardly spaced relation to the elevated end of the elevated flange 20. The upper end of 25 the upper flange 20 has a downturned upper stop flange 24 while the depressed end of the lower flange 21 has an upturned stop flange 25, the stop flanges 24 and 25 being spaced to snugly engage the upper and lower edges, respectively, of the 30 louver 11 when inserted between the flanges 20 and 21.

The depressed end of the upper flange 20 of the holder section B is spaced upwardly or laterally inwardly from the depressed end of the lower flange 21 and is bent upwardly and inwardly to provide a lower hook 26. At a point intermediate its elevated and depressed ends the upper flange 10 is slit transversely to define a lower transverse edge 27 in the plane of the flange 20 and the upper edge 28. A portion 30 adjacent to the upper edge 28 is directed upwardly at right angles from the flange 20 to define a shoulder, and the shoulder 30 terminates at its upper end in a downwardly directed terminal 29 which is parallel to the flange 20 and is upwardly spaced from the flange 20 at a distance such that the flange 19 of the bracket section A can be snugly and frictionally received between the terminal 29 and the upper surface of the flange 20. The shoulder 30 is spaced upwardly from the lower hook 26 at a distance corresponding to the length of the bracket section flange 19 so that when the bracket flange 19 is engaged between the shoulder 30 and the stop hook 26 there is a minimum 45 of lost motion of the holder section 3 in a direc-

tion lengthwise of the bracket section flange 19. The stop hook 26 is not initially in the form of a hook, but in the form of a straight piece extending upwardly from the depressed end of the flange 28, the terminal part of the piece being adapted to be bent downwardly or laterally inwardly to form the stop hook 26.

Two of the bracket sections A having been mounted in longitudinal alignment on the window frame side members 10, and holder sections B having been slipped onto the opposite ends of a louver 11, the louver is installed by passing the holder sections B upwardly under the flanges 19 of the bracket sections A and engaging the terminals 29 over the elevated ends of the portions of the flanges 20 which are below the shoulders 30. Then, with the shoulders 30 engaging the said elevated edges of the flanges 28, the lower portions of the flanges 20 are brought up against the undersides of these portions of the flanges 20, whereupon the terminal or free end portions of the pieces 26 are bent laterally inwardly over and downwardly upon the depressed ends of the bracket flanges 19, and preferably squeezed tight to securely grip the flanges 19 and form the lower hooks.

In the event that it be desired to remove the louver 11, it is necessary only to bend up the terminal or free end portion of the hook 26. This frees the holder sections B to be removed from the flanges 19 of the bracket sections A by a removal of the louvers, described above. It is to be observed that in installing and removing a louver no manipulation of, or mutilation of the bracket sections A is involved, and that, in the event that the hook 26 of any holder section should break off in being bent in installing or removing a louver, the offending holder section B can be readily removed and replaced relative to the louver, without in any way involving the bracket sections A on the window frame side members 10.

What is claimed is:

1. In a louver clip, a bracket section and a holder section, said bracket section comprising a mounting plate adapted to be secured to a side of a lower opening and a lateral flange projecting at right angles from said mounting plate so as to extend into the lower opening, said lateral flange having a free end remote from the mounting plate and having opposed side edges, said side edges being substantially parallel to each other, said holder section comprising a channel form comprising a web, upper and lower flanges projecting laterally from said web, said upper and lower flanges being spaced from each other to snugly receive a louver end therebetween, stop members on opposed ends of said upper and lower flanges for engagement with opposed side edges of a louver, said upper flange having upwardly projecting and facing hooks thereon, said hooks being spaced from each other and slidably engaging the top and the opposite side edges of the lateral flange of the bracket section with the upper side of the upper flange of the holder section slidably engaging the under side of the lat-

eral flange of the bracket section, the holder section being removable from the bracket section by movement of the holder section laterally in a direction away from the mounting plate of the bracket section.

2. In a louver clip, a bracket section comprising a mounting plate and a lateral flange projecting at right angles from one side of the mounting plate, said lateral flange having a free end remote from the mounting plate and parallel opposite side edges, said holder section comprising a channel form comprising a pair of parallel spaced flanges arranged to receive a louver end therebetween, stop members on opposed ends of said flanges for engaging opposed side edges of a louver, and a pair of hooks on one of said flanges, said hooks being located on the side of said one flange remote from the other flange of the pair, said hooks being spaced from each other and engaging the said opposite side edges of the lateral flange of the bracket section with the said remote side of said one flange bearing against a side of said lateral flange, said hooks having terminals engaging over the opposite side of said lateral flange.

3. In a louver clip, a bracket section comprising a mounting plate and a lateral flange projecting at right angles from one side of the mounting plate, said lateral flange having a free end remote from the mounting plate and parallel opposite side edges, said holder section comprising a channel form comprising a pair of parallel spaced flanges arranged to receive a louver end therebetween, stop members on opposed ends of said flanges for engaging opposed side edges of a louver, and a pair of hooks on one of said flanges, said hooks being located on the side of said one flange remote from the other flange of the pair, said hooks being spaced from each other and engaging the said opposite side edges of the lateral flange of the bracket section with the said remote side of said one flange bearing against a side of said lateral flange, said hooks having terminals engaging over the opposite side of said lateral flange, one of said hooks being bendable out of engagement over the said opposite side of the lateral flange of the bracket section.
